UNITED STATES PATENT OFFICE.

GILBERT G. DAVIS AND MATTHEW J. DAVIS, OF PORTLAND, OREGON.

LOG RAFT AND RAFTING DEVICE.

Application filed November 21, 1923. Serial No. 676,124.

To all whom it may concern:

Be it known that we, GILBERT G. DAVIS and MATTHEW J. DAVIS, both subjects of the King of Great Britain, and both residents of the city of Portland, in the State of Oregon, United States of America, have invented certain new and useful Improvements in Log Rafts and Rafting Devices, of which the following is a specification.

10 Our invention relates to improvements in log rafts and rafting devices, the objects of which are to enable very large quantities of logs to be formed into rafts for transportation through open waters, other objects 15 being to provide means whereby the rafts may be so rafted as to form a symmetrical body with relatively smooth sides and bottom that the friction of the water thereagainst is reduced to a minimum also to provide 20 vessels to enclose the ends of the logs so rafted that the raft may be easily towed at reasonable speed with a minimum of towing effort, a further object is to so construct 25 the rafting devices that they may be coupled together after dismantling the raft and utilized on the return journey as barges.

The invention consists essentially of a pair of open ended vessels having watertight floor compartments and logs formed into a 30 raft in such a manner that the ends of the raft are held in position within the open ends of the vessels, and means for binding the raft together, and the vessels together so that the strains imparted to the raft and 35 its vessels by the action of waves tends to tighten the bindings, as will be more particularly described in the following specification in which:—

Fig. 1 is a longitudinal sectional view of 40 the invention.

Fig. 2 is a plan view.

Fig. 3 is a side view.

Fig. 4 is an enlarged transverse sectional view.

Fig. 5 is a part sectional view showing 45 the manner in which the rafting devices are coupled together for returning to starting point.

Fig. 6 is a fragmentary sectional view of 50 the coupling means.

In the drawings like characters of reference indicate corresponding parts in each figure.

The numerals 1 and 2 indicate the forward and rear ends respectively of the rafting devices which are open ended vessels

similar to the bow and stern sections of a barge, the floor of each being provided with a plurality of watertight compartments 3, 4 and 5 into or out of any of which water may be pumped by any suitable means so as to sink or raise the vessels 1 and 2, and to trim them that they may be conveniently loaded or that they may be connected together for the return tow. The numeral 6 indicates the bottom wall, 7 the side walls and 8 the floor, the end wall 9 of the compartment 5 is set back from the end of the bottom wall 6 to form a ledge 10 on which the floor logs of the raft are laid. 11 indicates an upstanding angle iron which is riveted to the open end of the bottom wall 6 and the side walls 7 which serves as a means whereby the vessels 1 and 2 are connected together to make a watertight joint and also to form a gripping connection with the ends of the logs forming the bottom and sides of the raft. 12 (see Figs. 5 and 6) indicates a plurality of lugs upon the floor 8 and the inside of the side walls 7 through each pair of which a bolt 13 is passed for coupling up the vessels 1 and 2 to form a barge for return cargo. 14 indicates a pair of hawse pipes through which tow or anchor ropes are passed. Within each of the vessels 1 and 2 are provided a plurality of ring bolts 15 to which blocks 16 and 17 are fastened, the purpose of which will hereinafter appear. 18 indicates further eyes or ring bolts upon the inside of the walls 7 for the attachment of the longitudinal binding ropes 32.

As a means for providing lateral stability to the vessels 1 and 2 transverse bridges 19 are erected which bind the side walls 7 against spreading strains, such bridges being supported from the floor 8 by a plurality of stanchions 20 which also serve to define substantially rectangular spaces 21 through which the ends of the logs extend thus forming a substantial clamping effect to different groups of logs adjacent their ends which materially reduces any tendency of the intermediate portion of the raft to twist.

The numeral 22 indicates a plurality of suitably driven winches by which any of the ropes may be tightened either during raft construction or during towing.

The numeral 23 (see Fig. 4) indicates a plurality of logs forming the floor of the raft, one end of each of the logs adjoining

23
 the vessels 1 and 2 being laid to abut the outer end of compartments 5, a side of the logs resting upon the bottom 6 of the vessels so that the underside of the floor formed by such logs is level with the bottom of the vessels 1 and 2. The web of the angle irons 11 cuts into the logs as successive tiers of logs are laid up, thus forming a positive connection between the vessels and the logs of the floor and sides of the raft. The floor logs 23 are transversely bound together by ropes 24 which are passed alternately over and under the logs, the ropes being clamped together adjacent the sides of the raft as at 25 and the ropes laid out for further use on the raft sides. It will be understood that the logs are not necessarily continuous from end to end of the raft but may be run in various lengths with the ends of one row overlapping the ends of another row and sufficient transverse bindings being used to hold the several logs together as a body. When the floor logs are in position and are transversely bound together at suitable intervals, the other logs indicated generally by the numeral 26 are laid upon them and side logs 27 are built up and bound together with the ropes 24 in a similar manner to that employed with the floor logs, the ends of said side logs passing into the vessels 1 and 2 and being gripped also by the webs of the angle irons 11. 28 indicates binding ropes by which corresponding logs in opposite side walls are held against lateral spreading.
 35 When a suitable number of logs have been evenly laid upon the floor logs, ropes 29 are secured to ring bolts 15 upon the floor of vessel 1 which is run lengthwise of the raft through blocks 17, inside vessel 2 and thence 40 back along the raft and are passed out through the hawse pipe 14 for attachment to the rope of the tug; similar ropes 30 are attached to ring bolts 15 upon the floor of the vessel 2 run lengthwise of the raft through 45 blocks 16 of the vessel 1 and back to the vessel 2 where it passes through suitable leads or blocks and is attached to a winch 22 by which it is drawn taut at the completion of the raft construction to bind the 50 vessels firmly to the ends of the raft of logs.
 At suitable intervals in the height of the raft and also when the raft is entirely built, binding ropes 31 are passed down one side under the floor logs up on opposite sides of the raft and are drawn tight to securely bind the several logs together and are clamped together upon any desired tier of logs 26.
 As a further means of securing the vessels 1 and 2 to the raft of logs a pair of ropes 32 are attached (on both sides of the raft) to opposing ring bolts 18 inside of the side walls 7, which ropes are stretched as tightly as possible; when a binding rope 33 is shackled adjacent the mid-length of the upper rope of 65 each pair, the rope passing under the raft up

the opposite side and over the top whence it passes around the lower rope of the pair and is brought back onto the top of the raft and clamped upon itself. The raft may be bound at any desired interval of its height or its 70 length.

In order that the bindings may be more clearly followed in Fig. 4, but one pair of ropes 32 with its binding rope 33 is shown, though similar ropes will be applied to 75 tighten the vessels 1 and 2 together on the opposite side of the raft.

Having thus described the several parts of our invention and the manner in which it is constructed we will now briefly explain 80 the manner in which it is towed, dismantled at destination, and the vessels 1 and 2 assembled for the return passage.

In towing the free ends of the ropes 29 are preferably coupled together and a block, 85 attached to the tow line of the tug, is applied to the bight so formed so that the pull of the tug is evenly exerted upon both of the ropes, such strain being constant suffices to automatically tighten up the raft in 90 an endwise direction, if found desirable during the towing period any slack developing on any of the other ropes may be taken up by means of the winches 22.

The raft can be quickly dismantled by releasing the several binding means and allowing the logs to fall apart. 95

When all of the logs have floated clear of the vessels 1 and 2, water is admitted to or removed from the compartments 3, 4 and 100 5 until they float on an even keel, when they are brought together and coupled by the bolts 13 as shown in Fig. 5, it then suffices to pump out any water from the interior 105 when any suitable cargo may be stowed therein and the vessels used on the return as a barge.

It will thus be seen that we have invented means which will enable large rafts to be formed for towing in ocean waters with a 110 minimum towing effort and which can be used as a cargo carrying barge when being returned to the point of primary loading.

What we claim as our invention is:
 1. The combination with a longitudinally 115 arranged log raft having floor logs and side wall logs, of a pair of open ended vessels into which the ends of the raft are adapted to rest, and means surrounding the open ends of the vessels for engaging the ends of 120 the floor and side wall logs.

2. The combination with a longitudinally arranged log raft, and a pair of open ended vessels in which the ends of the raft are adapted to rest, of a tow rope secured to 125 the interior of one vessel extending longitudinally of the raft and through a block in the interior of the other vessel and from thence back to the first named vessel and through a hawse pipe therein. 130

3. The combination with a longitudinally arranged log raft and a pair of open ended vessels in which the ends of the raft are adapted to rest, of ropes attached to the interior of one of the vessels extending longitudinally of the raft and through blocks in the interior of the other vessel and from thence back to the first named vessel and means for connecting the cable of the towing tug thereto to equalize the strain on said ropes.

4. A log rafting device comprising a pair of open ended vessel-like units, and means for connecting the open ends of the units together to form a single floatable vessel.

5. The combination of a log raft, vessel members housing the ends of the raft, winches carried by one of said vessel members and ropes secured at one end to said winches and at the opposite end to one of said vessel members, the intermediate portions of said ropes being trained around pulleys carried by both of the vessel members and serving to draw the latter together when the ropes are tightened by manipulation of the winches.

6. The combination of a log raft, vessel members housing the ends of the raft, longitudinal ropes connecting the sides of the vessel members at each side of the raft, a transverse rope passing beneath the raft and connected between opposite longitudinal ropes, additional longitudinal ropes passing through the raft and connected at one end to one of said vessel members with

the intermediate portions of the ropes trained around pulleys carried by both of the vessel members interiorly thereof and at opposite ends of the raft and rope tightening means carried by one of the vessel members and connected to the remaining ends of the last mentioned ropes.

7. The combination of a log raft, vessel members housing the ends of the raft, said raft consisting of an outer series of logs bound together and extending across the bottom and forwardly along the sides of the vessel members to form the bottom and sides of the log raft, tiers of inner logs constituting the center of the raft disposed upon the bottom logs and between the side logs of said outer series, suitable means securing all of said logs together in raft formation and means for securing the vessel members to the raft.

8. The combination of a log raft, vessel members formed to enclose the ends of the raft cable means for tying the vessel members together when engaged with the raft and independent means for directly coupling said vessel members to form a complete vessel serviceable independently of the raft.

Dated at Newport, Oreg., this 22 day of October, 1923.
